SPRING ASSEMBLY

George E. Taylor, Chicago, Ill., assignor to Samuel E. Sosna and George E. Taylor, copartners doing business as Chicago Upholsterers Supply Company, Chicago, Ill.

Application April 5, 1937, Serial No. 135,018

2 Claims. (Cl. 155—179)

This invention relates to spring assemblies of the kind particularly adapted for use in articles of furniture such as chairs, davenport, etc., and in spring-filled cushions for use in furniture and 5 in automobile seats and the like.

Spring assemblies embodying this invention generally comprise transversely and longitudinally extending rows of convolute springs having cross members such as cords or the like extended 10 across the springs and connected thereto to retain the springs in position. The springs are mounted on a frame generally made of wood but sometimes made of metal and a border wire generally extends around the spring assembly at the 15 tops of the springs. The spring assemblies receive their hardest usage along the front edge thereof and it is desirable to strengthen this front edge to compensate for this usage. It is also desirable in many instances that the border wire 20 extend forwardly of the front edge of the frame so that when the springs are compressed by a person sitting on the springs the front edge of the frame will not engage the legs of the individual. Small coil springs have been used to 25 reinforce the front edge of the spring assembly but these springs must necessarily extend vertically above the front edge of the frame and therefore cannot extend forwardly of this front edge. A space equal to a square whose sides are 30 equal to the diameter of the coil of these auxiliary springs must be provided if they are to be used.

The primary object of this invention is to reinforce the front edge of a spring assembly without enlarging the area of the frame.

Another object is to reinforce the front edge of a spring assembly with spring means which will not necessitate the provision of additional space for the reenforcing means.

A further object is to reinforce the front 40 edge of a spring assembly including the front part of the border wire where the border wire extends forwardly of the frame.

A still further object is to reinforce the front 45 edge of a spring assembly including the front part of the border wire with spring reenforcing means and wherein the front part of the border wire extends forwardly of the frame and without providing additional space on the frame to accommodate the reenforcing means.

A selected embodiment of the invention is illustrated in the accompanying drawing wherein

Fig. 1 is a perspective view of a covered spring assembly showing the cover partly broken away; 55 Fig. 2 is an enlarged fragmentary front eleva-

tion of one corner of the spring assembly and showing the spring reenforcing means;

Fig. 3 is an enlarged fragmentary side elevation of one corner of the spring assembly and showing the spring reenforcing means; and

Fig. 4 is a perspective view of the reenforcing spring.

In the accompanying drawing I have shown a frame 5 on which a plurality of convolute springs 6 are mounted in side by side relation and in rows. 10 The springs 6 are retained in place by cords 7 tied thereto and by a border wire 8 around the spring assembly at the top the springs. The border wire is fastened to the outside spring of the spring assembly by clips 9. I preferably arrange 15 the front part of the border wire forwardly of the front part of the frame (Figs. 1 and 3) so that an individual sitting on the springs will not engage the front part of the frame with his legs.

A reenforcing spring 10 comprises a coil 11, an upper arm 12 and a lower arm 13. The arms 12 and 13 have end portions 14 and 15 respectively bent at right angles to the arms and inwardly of the spring assembly. The ends of the end portions 16 and 17 respectively are bent back 20 in the same general direction as the arms 12 and 13. A hinge clamp 18 is secured to the frame and engages the end portion 15 of the spring 10, which end portion forms the pintle of the hinge. The arm 12 is secured to the side part of the border 25 wire near the free end of the arm by a clip 19 and the end portion 14 is secured to the front part of the border wire by another clip 20. The bent ends 16 and 17 of the spring 10 prevent the spring from becoming detached from the spring 30 assembly by slipping out of the clips 20 and hinge 18. The end portion 14 of the spring 10 extends forwardly of the front part of the frame while the end portion 15 is secured on the front part of the frame rearwardly of the forward edge 40 thereof. This construction raises the coil to within relatively close proximity to the side part of the border wire.

An individual sitting on the spring assembly will compress the convolute springs 6 and will 45 lower the forward part of the border wire. This action winds up the coil 11 as the arm 12 and its end portion 14 are secured to the front part of the border wire. When the individual rises from the seat the front part of the border wire is 50 snapped up into normal position by the unwinding of the coil 11 and the reenforcing spring 10.

My invention provides a spring assembly wherein the front border wire is adequately reinforced so that there will be no sagging of the 55

border wire after continued use of the spring assembly. The invention also provides a reenforcing spring which can be applied to spring assemblies of the present type of manufacture without enlarging the frame or making other provision to permit enough space for use of a reenforcing spring. The invention further provides for a reenforcing spring which will reinforce the front part of a border wire that is arranged forwardly of the front part of the frame. The long lever arm of the arm 12 of the reenforcing spring 10 insures the immediate resumption of normal position by the spring assembly upon the removal of the weight of an individual therefrom.

15 While I have illustrated and described a selected embodiment of my invention it is to be understood that this is capable of variation and modification and I therefore do not wish to be limited 20 to the precise details set forth but desire to avail myself of such changes and alterations as fall within the scope of the following claims:

I claim:

1. In a spring assembly consisting of a bottom 25 supporting frame, a top border reinforcing wire spaced from said frame, and a plurality of springs mounted in the frame, a wire reinforcing spring and means for securing the reinforcing spring

to the frame and border wire; the reinforcing spring consisting of two arms at substantially right angles to one another with an intermediate coil formation integral therewith, the end portion of each arm extending laterally in the same direction with respect to said arms, one laterally extending portion of the reinforcing spring being secured to and parallel with an end portion of the front of the top border wire and extending around an end corner of the top border wire and secured 10 to a side end portion of the top border wire and extending downwardly to said coil formation, and the other laterally bent portion secured to the said frame thereby disposing the coil formation between the top border wire and the frame at 15 one corner thereof in spaced relation to said border wire and said frame whereby to permit flexing of both of said arms and to reinforce the corner of the border wire, and the extreme ends of the arms extending at substantially right 20 angles with respect to each laterally extending portion thereof, thereby preventing dislodgment from the said securing means.

2. A structure as defined in and by claim 1, wherein the said other laterally bent portion is 25 hingedly secured to the frame.

GEORGE E. TAYLOR.
